CLAIM

The ornamental design for a seat assembly, as shown and described.

DESCRIPTION

FIG. 1 is a perspective view of a seat assembly as seen from the top, front and left sides;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken line showings in the figures are for illustrative purposes only and form no part of the claimed design.
